UNITED STATES PATENT OFFICE.

HARRY BENDA MILES, OF ELWOOD, VICTORIA, AUSTRALIA.

DESIGN FOR A TALKING-MACHINE CABINET.

55,871.

Specification for Design.

Patented July 20, 1920.

Application filed December 18, 1919. Serial No. 345,905. Term of patent 14 years.

To all whom it may concern:

Be it known that I, HARRY BENDA MILES, a subject of the King of Great Britain, and a resident of 44 Ormond road, Elwood, in the State of Victoria, Commonwealth of Australia, have invented a new, original, and ornamental Design for Talking-Machine Cabinets, of which the following is a specification, reference being had to the accompanying drawing, forming part thereof.

The figure is a perspective view of a talk-

ing machine cabinet formed wedge shape to adapt same to fit into the corner of a room and showing my new design.

I claim:—

The ornamental design for a talking machine cabinet, as shown.

HARRY BENDA MILES.
